UNITED STATES PATENT OFFICE.

JOB A. DILLON, OF TECUMSEH, NEBRASKA.

CLAMP.

1,109,741.

Specification of Letters Patent.

Patented Sept. 8, 1914.

Application filed May 16, 1914. Serial No. 839,101.

To all whom it may concern:

Be it known that I, JOB A. DILLON, a native-born citizen of the United States, residing at Tecumseh, in the county of Johnson and State of Nebraska, have invented 5 certain new and useful Improvements in Clamps, of which the following is a specification, reference being had to the accompanying drawings.

10 This invention relates to clamps, and particularly to clamps which are adapted for use in connection with wire stretchers to hold the wires of a fence while they are being stretched.

15 An object of this invention is the provision of a clamp of this character which comprises a pair of bars having registering openings formed therein to receive the bolts upon which the clamping nuts are mounted, 20 means being provided whereby one of the bars may be removed or applied to the bolts without disengaging the bolts from the other of the bars.

25 A further object of this invention is the provision of a clamp of this character which comprises a pair of bars, one of the bars having a plurality of circular openings therein and the other bar having a plurality of elongated openings therein which register 30 with the circular openings in the first bar, the registering openings being adapted to receive bolts upon which the clamping nuts are mounted, each of the bolts having one 35 end angularly disposed so that the same may be turned to allow the bar having the elongated openings to be passed over the angularly disposed portions of the bolts without disengaging the bolts from the bar having the circular openings therein.

40 With these and other objects in view, my invention consists in the novel construction, combination, and arrangement of parts to be hereinafter more fully described, claimed, and illustrated in the accompanying drawing, in which,

45 Figure 1 is a rear elevational view of my improved clamp; Fig. 2 is a front elevational view thereof; and Fig. 3 is a sectional view on the line 3—3 of Fig. 2.

50 Referring more particularly to the drawing, the numerals 1 and 2 designate a pair of clamping bars which are adapted for use in connection with a wire stretcher of any desired construction, to grip the wires of a 55 fence therebetween, the bar 1 having a plurality of horizontally disposed circular

openings 3 formed therein, and the bar 2 having a plurality of elongated openings or slots 4 formed therein which are spaced the same distance apart as the openings 3 in the bar 1 to register therewith. Disposed through the openings 3 in the bar 1 are bolts 5 which are threaded as at 6, at one end to receive the nuts 7 which are provided with turning handles 8, the other end of each bolt 65 being provided with an angular extension 9, the extension 9 being of a length slightly less than the length of the elongated openings 4 in the bar 2 so that the bolts may be turned to dispose the extension 9 longitudinally of the bar 1 whereby the bar 2 may be engaged against the bar 1 by passing the slots 4 over the extensions 9 of the bolts. The bar 2 is provided on its outer face with transversely extending grooves 10, each 75 groove extending across one of the slots 4 at its upper end, one end of each groove being adapted to receive the angular extension of one of the bolts after the bar 2 has been engaged against the bar 1 to prevent accidental separation of the bars.

80 In the practical use of my improved clamp, when it is desired to connect the same to the wires of a fence, the bar 2 is disengaged from the bar 1 and the bar 1 is 85 placed so that the wires engage the inner face of the bar, whereupon the bolts are disposed so that the extensions 9 thereof extend longitudinally of the bar and the bar 2 is engaged against the wires with the 90 bolts projecting through the slots 4. In this position, the bolts are turned so that the extensions 9 are disposed transversely of the bar 2 to engage in one end of the grooves 10, whereupon the nuts 7 are tightened 95 against the outer face of the bar 1 to securely clamp the wires of the fence between the bars. In the usual construction of wire clamps for stretchers, two men are necessary to operate the same, one to hold 100 the bolts to prevent them from turning while the other turns the nuts tightly against one of the bars, while in a clamp constructed in accordance with my invention, one man can easily operate the device to clamp the wires 105 of a fence between the bars as the grooves 10 in which the extensions 9 of the bolts engage prevent turning of the bolts, while the nuts are being turned flush against the outer face of the bar 1. The bolts used in connection with clamps of ordinary construction must also be entirely removed from the 110

bars when the same is separated while in my improved clamp it will be seen that the bolts are always carried by the bar 1 having circular openings therein, so that all danger 5 of the bolts becoming lost or misplaced is obviated.

Having thus fully described my invention what I desire to claim and secure by Letters Patent, is:—
10 A clamp of the character described comprising a pair of bars, one of said bars having a circular opening therein, the other of said bars having an elongated opening therein for registration with the opening in
15 the first mentioned bar, a bolt having a lat-

erally disposed head arranged through said registering openings, said second mentioned bar having a transversely disposed groove formed in its outer face and crossing said elongated opening at one end thereof, said groove being adapted to receive the head of the bolt when the bars are connected together, so that the head is maintained out of alignment with the elongated opening.

In testimony whereof I hereunto affix my 25 signature in the presence of two witnesses.

JOB A. DILLON.
